UNITED STATES PATENT OFFICE

JOHN HUTCHINSON REID, OF JAMESTOWN, NORTH DAKOTA

MANIFOLDING CARBON PAPER

Application filed December 12, 1928. Serial No. 325,809.

My invention relates particularly to mani-
folding carbon paper such as is most largely
used in typewriting for production of dupli-
cate impressions; and my object is to provide
5 in a simple and economical way for enabling
the easy separation of the piled sheets.

The inconvenience and loss of time com-
monly involved in effecting such separation
has been recognized, and effort has been made
10 to facilitate the operation by providing spe-
cially shaped carbon sheets adapted to enable
independent gripping and removal of them
without the usual complete disarranging of
the typed sheets between which they are in-
15 terposed. Such efforts however have hereto-
fore involved offsetting disadvantages par-
ticularly as to cost of the special carbons,
which have prevented the satisfactory rem-
edying of the trouble which my simple inven-
20 tion practically accomplishes as hereinafter
fully set forth in connection with the accom-
panying drawing and as clearly defined in
the subjoined claim.

Fig. 1 is a plan view of a manifolding sheet
25 of carbon paper formed in accordance with
my invention; and Fig. 2 is a diagrammatic
view of a large sheet of carbon paper showing
the lines on which a number of the mani-
folding sheets are simply cut therefrom so
30 as to form each of the latter as shown in Fig.
1 without waste of material.

Facilitating of the separation of the car-
bon sheets from the impression sheets with
which they are piled may obviously be pro-
35 vided for by enabling independent gripping
of the two sets of sheets, so as to permit with-
drawal of the carbon sheets jointly and with-
out substantially disarranging the impres-
sion sheets. The accomplishment of this in a
40 practically satisfactory way however, re-
quires in the first place that the gripping and
withdrawing action be most effectively and
safely exerted to overcome the slight adhe-
sion between the piled sheets; in the second
45 place that any special forming of the sheets
be simple and unobjectionable in the handling
of them; and in the third place that such
special sheets be furnishable without objec-
tionable increase in cost of production or de-
50 crease in their useful life. Unless these re-

quirements are met the obvious advantages
sought for are so balanced by the disadvan-
tages as to prevent practical solution of the
problem; which latter my simple improve-
ments actually provide for. 55

The rectangular form of the ordinary
manifolding carbon sheet is retained in my
simply improved form as separately shown
in Fig. 1, excepting as to the one end-edge
portion *a*; which latter alone is specially
60 formed so as to provide for enabling inde-
pendent gripping of the carbon sheets and
of the impression sheets piled therewith.
This provision consists simply of a lateral
grip-extension *b* on one corner, and a corre-
65 sponding cut-away *c* on the laterally oppo-
site corner of the top edge *a* of the sheet; this
arrangement leaving edges *d* and *e* of the
sheet, clear of any interference with the usual
tapping operation for evening the piled sheets 70
both endwise and laterally; and also provid-
ing for the exerting of the separating pull
in the line of least resistance, that is cross-
wise of the sheets and along one edge *a* there-
of so that the least adhering resistance needs 75
to be overcome in the initial changing of the
relative positions of the otherwise easily mov-
able sheets. The shape and size of the lat-
eral grip-extension *b* may be such as to pro-
80 vide for very satisfactory gripping without
objectionable effect; and also without involv-
ing waste of material as is particularly
brought out in connection with Fig. 2. As a
matter of fact this grip-extension may be
85 made of sufficient size to enable its folding-
over if desired, on the upper carbon sheet of a
pile, for preventing finger contact with the
carbon surface in withdrawing the sheets,
without interfering at all with full use of the
90 sheet in making impressions or with economic
production of the sheets.

As already stated, this matter of economic
production of the sheets is of practically vital
importance in attaining desired facility of
sheet separation—the importance of the lat-
ter being unduly belittled when opposed by
95 increased cost of material.

This objection is practically eliminated in
the manufacture of my simply but impor-
tantly improved sheets, as is clearly indi- 100

cated in Fig. 2. In cutting the small mani-
folding sheets shown in Fig. 1, from a large
sheet or roll indicated in Fig. 2, the forming
of the grip-extensions *b* and of the corre-
sponding cut-aways *c*, on laterally-opposite
corners of one end edge *a*, is accomplished as
indicated without involving any waste of ma-
terial, the material which forms each grip
extension being provided by the cut-away
from an unusable portion of an adjacent
small sheet, and such corresponding cut-away
in the latter serving the essential purpose of
providing for independent gripping of the
impression sheets with which it is to be piled
in service.

10 It will be seen that the apparent simplicity
of my invention is in fact an essential to prac-
tical solution of a simple but annoying prob-
lem heretofore sought to be solved without
the actual success attained by my improve-
ments.

15 What I claim is:

20 A manifolding carbon sheet of rectangular
shape, having an end portion thereof formed
25 with a cut-out on one side and a grip-exten-
sion on the opposite side, said cut-out and
grip-extension being identical in form and
size.

20 In testimony whereof I affix my signa-
ture.

JOHN HUTCHINSON REID.
